UNITED STATES PATENT OFFICE

WILLIAM C. KINGGETT, OF OAKLAND, CALIFORNIA

DESIGN FOR A COMBINED RADIO CABINET AND DESK

Application filed February 18, 1931. Serial No. 38,716. Term of patent 14 years.

To all whom it may concern:

Be it known that I, WILLIAM C. KINGGETT, a subject of the King of Great Britain, and a resident of Oakland, in the County of Alameda and State of California, have invented a new, original, and ornamental Design for Combined Radio Cabinet and Desk, of which the following is a specification, reference being had to the accompanying drawing, forming part thereof.

Figure 1 is a perspective elevation of a

combined radio cabinet and desk embodying my new design, and arranged for the use thereof.

Figure 2 is a perspective elevation of the structure shown in Figure 1, but with radio and desk portions thereof closed.

I claim:

The ornamental design for a combined radio cabinet and desk substantially as shown.

WILLIAM C. KINGGETT.
